UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

CRINKLING PAPER.

Application filed October 23, 1920. Serial No. 418,961.

To all whom it may concern:

Be it known that I, WILLIAM A. LORENZ, a citizen of the United States, residing in Hartford, in the county of Hartford and State of Connecticut, have invented certain new and useful Improvements in Crinkling Paper, of which the following is a specification.

This invention relates to means for crinkling or otherwise forming or working paper.

It is the practice to dampen paper as it advances from the supply-roll and lead the moistened paper around a cylinder, and crush it against a stationary doctor-blade which both crinkles the paper in lines transverse to the web and strips the same from said cylinder. In many instances, as for example, when the paper web is sized too highly, the water does not work well into the paper before the latter is delivered onto the surface of said crinkling cylinder.

The further difficulty arises, that where the water permeates the paper, the latter expands locally, and as the consequence of such expansion, irregular wrinkles are formed longitudinally and diagonally in the web, which spoil the appearance and depreciate the value of the finished crinkled paper.

One of the objects of the invention is to avoid the formation of such wrinkles, which usually extend irregularly along the web. To this end, there are formed numerous fine grooves in the cylinder, placed closely together, and preferably running around the cylinder; and there is arranged a soft roll or device to press the paper against the cylinder and into the grooves, thereby forming lines in the web and taking up the lateral expansion thereof, due to the water soaking into its fibre; and by this means the formation of the above-mentioned irregular wrinkles is avoided.

Another feature of the invention relates to a preliminary treatment of the web, which has the advantage of rendering the web more permeable to water, this insuring a full and even dampening of the web, and moreover permitting the crinkling operation to proceed more rapidly; and this preliminary treatment otherwise brings the paper to better condition for crinkling or other working. This preliminary treatment involves the bending and breaking of the fibres of the paper. This may be done by passing the

web between pressure rolls which have fine surface corrugations. One pair of rolls may have the corrugations arranged longitudinally, and a second pair may have fine peripheral corrugations, so that the fibres may be bent or broken in lines transverse to one another. This renders the paper more permeable to water, and also in better condition to be crinkled by the doctor-blade, or otherwise worked. One of the advantages of the preliminary corrugating is that the paper may be brought to a dryer condition before it reaches the doctor-blade, so that the crinkled paper will be found to be more elastic and less apt to lose its shape or condition.

In the drawings there is illustrated a machine in which the paper is first corrugated longitudinally with fine corrugations, and then corrugated transversely with fine corrugations, and then moistened and then pressed into the fine peripheral corrugations on the crinkling cylinder, and finally crinkled against the doctor-blade; but it will be understood that features of the invention may be used without others, as for example, the preliminary corrugating of the web may be omitted in some cases; or the preliminary corrugating may be resorted to without dampening the web, or without afterward pressing the web into fine grooves in the crinkling cylinder; and the preliminary corrugations may be made either by the longitudinally grooved rolls alone or the peripherally grooved rolls alone, according to the work in hand.

Other features and advantages will hereinafter appear.

In the accompanying drawings,

Figure 1 is a plan of the preferred form of a machine for practicing the invention in one way.

Figure 2 is a sectional elevation taken at about line 2-2 Figure 1.

Figure 3 is a sectional elevation on a larger scale taken at about the line 3-3 of Figure 1.

Figure 4 is a sectional elevation of adjustable corrugating roll bearings taken at the line 4-4 of Figure 3.

Figure 5 shows a view on a larger scale of the preferred finely corrugated or knurled surface of the crinkling cylinder.

The paper is led from a supply-roll 10, which is retarded by a weighted brake-strap 11, and passes over an introductory roll 12,

and thence between a pair of finely lined grooved or knurled limbering rolls 13, 14, whereby the fibres of the web are bent or broken. Preferably the grooves 15 on the rolls 13, 14 are peripheral, whereby the web is longitudinally marked or fluted with slight fine corrugations, as seen at 16, Figure 1. The ridges on the roll 13 mesh with the grooves on the roll 14, and produce in the paper lines or fine corrugations that are so shallow that the paper is not ruptured, since there is no need to put undue strain or tension on the fibres.

The finely fluted web now passes between limbering rolls 17, 18, which are longitudinally grooved at 19, the rolls running in mesh whereby the longitudinal fluted web is also cross-corrugated or fluted, as at 20, Figure 1. This slight cross-corrugation completes the preparatory bending and breaking of the fibres of the paper which is now in condition to successfully undergo the subsequent operation or operations thereon. In the form of the invention illustrated, the web remains in flat condition at the completion of the fibre-breaking or bending process. It may be readily moistened, since it will rapidly absorb moisture applied thereto. The web is led from the rolls 17, 18, over a roll 21, or between roll 21 and a power-driven drum 22; water being applied to the cross-fluted paper from a sprinkler pipe 23. It will be understood that the paper may, if desired, be wet upon both sides before winding around said drum 22, and that the pipe 23 represents moistening means, whether the moisture is applied to one or both sides of the web.

The drum 22 is provided with a gear 24, with which meshes a drive pinion 25, connected to a drive pulley 26. A train of gears may connect the large gear 24 with the various rolls that operate upon the paper, an idle pinion 27 connecting the gear 24 to a drive pinion 28 on roll 17, and an idle pinion 29 connecting 28 to a drive pinion 30 on roll 15. It will be understood that the lower rolls 13, 14 are provided with drive pinions 30^a, 30^b, Figure 3, to mesh with 28, 30, respectively.

It will also be understood that the corrugations on the sheet, whether longitudinal or transverse or both, are of advantage in rendering the paper more permeable, or better adapted to absorb the moisture, even though the drum 22, which is a crinkling drum or cylinder, be provided with a smooth surface; but one of the improvements illustrated in the drawings consists in providing lines or fine peripheral superficial grooves 31 in said drum, into which the web is pressed by a soft rubber or other soft pressure roll 32. In forcing the paper into the grooves on the cylinder, the soft roll 32 tends to stretch the paper sidewise, and the

paper, because of its moist condition, is adapted to yield slightly to this stretching tendency. At the same time, wherever there happens to be any local expansion of the sheet due to the wetting, the effect of said roll 32 is to pack the excess of paper down into the grooves of the cylinder. This overcomes the tendency which would otherwise exist, of the locally over-expanded portions of the paper to produce serious folds or wrinkles in the web.

The paper is carried around by the cylinder 22 against a doctor-blade 33, which crinkles the paper transversely and strips it from the cylinder at 34; the crinkled paper being led away upon a delivery-belt mechanism 35.

It will be understood that the paper must be crushed against the stationary doctor-blade with some force, in order to effect the desired wrinkling. For this purpose, the paper must cling to the crinkling cylinder 22, and the adherence is secured partly by the moistening of the paper and partly by the pressing of the moist paper against the cylinder by the roll 32, the adherence becoming stronger by reason of the grooved condition of the cylinder, since the paper sticks more tightly when pressed into the grooves than would be expected when merely pressed against a smooth-surfaced cylinder.

The roll 32 may be driven by a pinion 36, meshing with the main gear 24. All of the rolls that operate upon the paper may be provided with pressure-regulating devices, seen at Figure 4. The end of the roll shaft 37 may rotate in a bearing block 38, which may be adjustable up and down in a housing 39, and may rest upon an adjustable support in the form of a screw 40. This permits the rolls in each pair to be set as closely together as desired. The pressure of one roll against the other is produced by a spring 41, whose power is regulated by screw 42 having a locknut 43.

Variations may be resorted to within the scope of the invention, and portions of the improvements may be used without others.

Having thus described my invention, I claim:

1. The process of crinkling a web, comprising bending or breaking the fibres of the web, applying moisture to the web, and then carrying the web against a doctor-device or obstruction to crinkle the same.
2. The combination of means to produce numerous fine preliminary corrugations or markings in a web, means for moistening the web, and means for crinkling the web.
3. The combination of means for producing numerous fine longitudinal corrugations in a web, means for producing numerous fine transverse corrugations in said web, and means for crinkling the web.

4. The combination of means for producing numerous fine longitudinal corrugations in a web, means for producing numerous fine transverse corrugations in said web, 5 means for moistening the web, and means for crinkling the web.
5. The combination of means for producing preliminary fine numerous markings in a web, means for moistening the web, 10 means for shrinking the moist web by forming corrugations or the like therein, and means for crinkling the web.
6. The combination of a pair of meshing corrugated rolls for corrugating a web 15 in one direction, a second pair of meshing corrugated rolls for corrugating the web in a transverse direction preparatory to working the web, means for moistening the web, and means for effecting the desired working 20 of the web.
7. The combination of a pair of meshing corrugated rolls for corrugating a web in one direction, a second pair of meshing corrugated rolls for corrugating the web in a 25 transverse direction preparatory to working the web, means for moistening the web, and means for crinkling the web transversely.
8. The combination of a pair of meshing corrugated rolls for corrugating a web in 30 one direction, a second pair of meshing cor-
- rugated rolls for corrugating the web in a transverse direction preparatory to working the web, means for moistening the web, a crinkling cylinder having numerous fine depressions therein, a soft device to press 35 against the paper and pack it into said depressions, thereby to shrink the paper or take up the lateral expansion thereof due to the moistening, and a doctor-blade or obstruction to co-operate with the cylinder to 40 effect the crinkling.
9. In a machine for crinkling paper, the combination of finely corrugated rolls for breaking the surface of sized paper or heavy paper, to facilitate the absorption of water 45 by the interior portions of the paper, means for applying moisture to the paper, and means for crinkling the paper, including a crinkling cylinder and a doctor-blade or crinkling device. 50
10. The herein-described process, comprising breaking the surface of sized or thick paper to allow moisture to penetrate the interior of the paper, wetting the paper, and crinkling or working the paper into the desired condition. 55
